UNITED STATES PATENT OFFICE.

JOHN WILLIAM WOODWARD, OF MONTREAL, QUEBEC, CANADA.

GARMENT HANGER.

1,417,009.

Specification of Letters Patent. Patented May 23, 1922.

Application filed March 28, 1921. Serial No. 456,305.

To all whom it may concern:

Be it known that I, JOHN WILLIAM WOODWARD, subject of the King of Great Britain, and residing at 2225 Waverley Street, in the city and district of Montreal, in the Province of Quebec, in the Dominion of Canada, have invented a new and useful Garment Hanger, of which the following is the specification.

10 The invention relates to garment hanger as described in the present specification and illustrated in the accompanying drawings that form part of the same.

15 The invention consists essentially of a novel form of holder that automatically falls to engagement with the garment and is manually released.

20 The objects of the invention are to firmly hold the garment without making undesirable creases and at the same time insure ready and instant release; to eliminate spring wire holders and clamps; to decrease the cost of production, and generally to provide a simple and effective garment hanger.

25 In the drawings Figure 1 is a perspective view of the hanger showing the leg portion of a pair of trousers held therein.

Figure 2 is a cross sectional view of the hanger in its closed position.

30 Figure 3 is a cross sectional view of the hanger showing the holder released.

Like numerals of reference indicate corresponding parts in each figure.

Referring to the drawings, the board or plate 1, having the hook 2 bent under at 3 and secured between the block 4 and the raised centre 5 of said board or plate 1, is formed to fit to the shoulders of a coat or otherwise according to the style of garment.

The arms 6 are secured to the block 4 40 and raised centre 5 and extend laterally from the board 1 and are turned downwardly and inwardly toward the said board and form the inclined sections and roller tracks 7.

The roller 8 is mounted on the tracks 7 45 and naturally falls to the bottom thereof and rests against the tracks and the board 1.

The roller 8 is closed in by the end walls 9, which leave a free garment space between themselves and the board. 50

The trousers 10 are introduced into this space and the roller 8 is temporarily held up, but allowed to drop to hold the trouser ends against the board 1 and it will be seen that no matter how hard the pull there can be 55 no release until the finger is inserted to hold the roller from engagement, while the trousers are removed.

Many changes may be made to suit different uses and materials, but the main features 60 will remain the same as pointed out in the claim for novelty following.

What I claim is:—

The combination of a coat hanger and a trousers hanger in which the frame of the 65 trousers hanger straddles the coat hanger, the latter projecting upwardly within the trousers hanger frame and having a suspension hook projecting therefrom, said trousers hanger frame being rigidly secured to the 70 hanger and having roller side guards and converging to said coat hanger to support a roller which forms the fastening member for the trousers.

Signed at Montreal, Quebec, Canada, this 75 eighth day of March, 1921.

JOHN WILLIAM WOODWARD.
